T. E. MURRAY.
VEHICLE WHEEL.
APPLICATION FILED MAY 28, 1915.

Patented Aug. 17, 1915.

Inventor
Thomas E. Murray
By his Attorney
Mark Benjamin

UNITED STATES PATENT OFFICE.

THOMAS E. MURRAY, OF NEW YORK, N. Y.

VEHICLE-WHEEL.

1,150,294.

Specification of Letters Patent. Patented Aug. 17, 1915.

Application filed May 28, 1915. Serial No. 30,935.

To all whom it may concern:

Be it known that I, THOMAS E. MURRAY, a citizen of the United States, residing at New York, in the county of New York and 5 State of New York, have invented a certain new and useful Improvement in Vehicle-Wheels, of which the following is a specification.

The invention relates to vehicle wheels of 10 metal, and has for its object to simplify and cheapen the construction.

The end of each spoke abuts against the tubular portion of an inner junction piece, integral with which are two parallel flat 15 plates in the shape of wedge frusta, having at their smaller bases concave outwardly turned flanges. The inner junction piece and the joint between the same and the spoke end is covered by an 20 outer junction piece of like form, with registering inclined edges, and seated on said flanges. The inclined edges of the junction pieces on the several spokes are united to form an annular nave, which is received 25 upon a tubular hub.

In the accompanying drawings Figure 1 is a face view of my wheel, the outer portions of the spokes shown being broken away and the rim omitted, and the inner 30 portion of one spoke with its junction pieces being shown in section. Fig. 2 is a section on the line 2, 2 of Fig. 1. Fig. 3 is a perspective view of the covering or outer junction piece. Fig. 4 is a perspective view of 35 the inner junction piece.

Similar letters of reference indicate like parts.

To each tubular spoke I are attached two members—hereinafter designated as the inner junction piece and the outer junction piece. The inner junction piece is preferably formed in two similar parts A, B, united on the line C and shaped as shown in 40 Fig. 4. The part A comprises a flat plate 45 in the form of a wedge frustum, the inclined side edges D of which meet at the smaller base an arc-shaped outwardly turned flange E. The part B comprises a similar flat plate, the inclined side edges F of 50 which meet an arc-shaped outwardly turned flange G. The larger bases of said plates are integral with a tubular portion H which at its end is of the same diameter as the tubular metal spoke I. The two parts A, B 55 are welded together at their joint C, and the

end of the spoke abuts against and is welded to the end of the tubular portion H. The angle of inclination of the side edges F is the same as that of the side edges D. The length of the flat plate of part B is less than 60 the length of the flat plate of part A.

The outer junction piece may be formed in two parts jointed in the same way as the inner junction piece described, or it may be made integrally in one piece, as shown in 65 Fig. 3. This comprises two flat plates J, K, also in the form of wedge frusta. The side edges L meet the smaller base M, which is concave and shaped in a circular arc. The two flat plates at their larger bases are integral with a tubular portion N. The constructive relation of the outer junction piece to the inner junction piece is to be such that when the outer piece is placed over the inner piece, as shown in Figs. 1 and 2, the inclined side edges of the plates of one piece 70 will register with the inclined side edges of the plates of the other piece, and the arc-shaped smaller base M of the outer piece 75 will fit upon the flanges E of the inner piece. 80 The tubular portion N of the outer piece, however, is to be long enough to extend over the circular upper edge of the inner piece, so that when the spoke is welded, as described, to said circular upper edge, the tubular portion N will cover the welded joint. 85 The outer junction piece is preferably spot-welded to both spoke and inner piece, so that when the spoke and the two junction pieces are assembled, they form a rigid 90 structure.

The tubular hub O at its inner end may be enlarged in diameter, as shown at P, and this enlarged portion is preferably not less in width than the flange G. The spokes 95 are assembled in forming the wheel by welding the inclined edges of the junction pieces attached to one spoke to the similar inclined edges of the junction pieces of the adjacent spokes, thus forming an annular nave, the joints between said junction pieces then lying in radii of a circle struck around the axle center. When the hub is inserted in the circular space bounded by the flanges E, G, the flanges G meet the enlarged portion P of the hub and the flanges E meet the body portion of the hub, as 100 shown in Fig. 2, and said flanges are welded to said hub, thus completing the wheel structure. Ball-bearing runways Q and R may 105 110

be inserted in each end of the hub to receive the axle S, and a cover T may be provided for the outer end of said hub.

I claim:

- 5 1. The combination of (1) a spoke, (2) a member formed with a tubular portion and two parallel flat plates in wedge frusta shape united to said tubular portion at their larger bases and provided with concave arc-shaped flanges at their smaller bases, and (3) a second member of form corresponding to said first member: the said first member being seated within said second member, the said spoke at its inner end abutting upon the end of the tubular portion of said first member, and the tubular portion of said second member inclosing the joint at said abutment: the said first member being seated within said second member, the said spoke at its inner end abutting upon the end of the tubular portion of said first member, and the tubular portion of said second member inclosing the joint at said abutment: and the said parts being homogeneously united.
- 15 2. A metal vehicle wheel, comprising (1) a plurality of spokes, and in combination with each spoke (2) a member formed with a tubular portion and two parallel flat

plates in wedge frusta shape united to said tubular portion at their larger bases and 25 provided with concave arc-shaped flanges at their smaller bases, and (3) a second member of form corresponding to said first member: the said first member being seated within said second member, the said spoke at its 30 inner end abutting upon the end of the tubular portion of said first member, and the tubular portion of said second member inclosing the joint at said abutment: the said members on each spoke being placed with 35 their inclined edges in contact with the inclined edges of the corresponding members of the next adjacent spokes to form unitedly an annular nave: and the said parts being homogeneously united.

In testimony whereof I have affixed my signature in presence of two witnesses.

THOMAS E. MURRAY.
